UNITED STATES PATENT OFFICE

2,487,430

FLAME HARDENING HEAD

Edgar M. Fein, Wellington, Kans., assignor to
 Cardwell Manufacturing Company, Inc.,
 Wichita, Kans.

Application April 7, 1948, Serial No. 19,503

1 Claim. (Cl. 266—4)

1

This invention relates to flame hardening heads and particularly to a device incorporating means for directing a heating flame toward a work piece and further means for directing a quenching fluid on to the heated work surface.

It is an object of this invention to provide such a flame hardening head wherein the work is quenched in stages.

It is a further object of this invention to provide a simple unitary structure which includes means for heating a work piece and subsequently partially quenching the heated surface and finally completely quenching the surface as the work piece is moved therepast.

It is a further object of this invention to provide a method of flame hardening which produces a satisfactorily hardened surface without the surface stresses incident to severe quenching of a heated work piece.

Further objects and advantages of the invention will become apparent as the description of a preferred embodiment proceeds in connection with the accompanying drawings, in which:

Fig. 1 is a front elevational view of an embodiment of the present invention as viewed from the position of the work piece;

Fig. 2 is a vertical sectional view taken substantially along the line 2—2 of Fig. 1; and

Fig. 3 is a fragmentary sectional view, on an enlarged scale, of one end portion of the flame hardening head and taken substantially along the line 3—3 of Fig. 2.

The flame hardening head of this disclosure comprises an elongated unitary body member 1 having therein a plurality of longitudinally extending and substantially parallel chambers 2, 3, and 4. Each of the chambers may be provided by milling through one surface of the member or may be originally cast therein, or provided in any convenient manner. Each of the chambers extends through a rear wall 5 of the member 1 and adjacent said rear wall each chamber is somewhat enlarged as indicated at 6. In each of the enlarged portions a closure 7 is fitted to define a completely enclosed chamber. The closures 7 are preferably of such a size as to be frictionally retained within the enlarged portions with sufficient force to withstand the internal pressures involved. The upper chamber 1 has a reduced portion 8 at the front thereof defining a shoulder 9 against which a baffle plate 10 is press-fitted and provided with a plurality of openings 11. Adjacent the middle portion of the elongated head conduit means 12 provide communication with the interior of the chamber 2. A plurality of longitudi-

2

nally extending rows of openings 13 extend from the forward portion 8 of the chamber 2 through the front wall of the unitary member, as shown in Figs. 1 and 2. The upper chamber just described constitutes a fuel chamber. The fuel is admitted from a suitable source (not shown) to the conduit 12, whence it is discharged into the chamber 2 and upon passing through the openings 11 the constituent parts thereof become thoroughly mixed. The fuel then passes through the openings 13 and issues therefrom in the form of jets directed toward a work surface. It will be clear that when such jets are ignited a sheet of flame will be directed toward the surface of a work piece to thereby heat the same.

The intermediate chamber 3 is provided with a row of openings 14 which, like the openings 13, are directed generally toward the work piece. The lower chamber 4 is provided with a plurality of rows of openings 15, which are also directed toward the work piece. A conduit 16 which is of generally Y-shape is in communication at its forked ends with the interior of the chamber 3 at the opposite ends thereof. The lower or stem portion of the conduit 16 communicates with a suitable source of supply (not shown) of a quenching medium to be supplied to the chamber 3. A similar conduit 17 is arranged to supply a second quenching medium to the lower chamber 4.

As clearly shown in Fig. 2, the front wall 18 of the member 1 is provided with a projecting portion 19 defining a ledge 20 adjacent the openings 13 and a lower sloping surface 21 through which the openings 14 and 15 extend. As shown, the openings 14 and 15, although directed generally toward the work piece, do extend in a direction slightly away from the openings 13. The chambers 3 and 4 will be filled with a quenching fluid under pressure, and as that fluid issues from the openings 14 and 15 it will impinge upon the surface of the work piece and a considerable quantity thereof will be splashed in all directions. The projection 19 and the ledge 20 will act to prevent the splashing quenching fluid from reaching the openings 13 and thereby extinguishing the heating flame.

It is contemplated that the structure just described be employed to harden a work piece that is mounted for movement past the face 18 of the member 1 in relatively close proximity thereto. In practice a hot quenching fluid will be supplied to the upper chamber 3 and a cold quenching fluid will be supplied to the lower chamber 4. As the work piece moves slowly past the flame hard-

ening head it will first become heated by the flame issuing from the openings 13 and the heated portion will then pass downwardly to a position where it is partially quenched by the hot quenching fluid issuing through the openings 14. However, after this partial quenching the work piece will still retain a considerable amount of heat, sufficient to effect "tempering" to relieve surface stresses that would otherwise develop if the work piece were completely quenched to room temperature in the first instance. After the partial quenching is accomplished the work piece moves into the final quenching zone, that is, to a position where the cold quenching medium issuing from the openings 15 will impinge thereupon and reduce the temperature of the work piece to its final low temperature.

The above described method and apparatus have been employed by using a mixture of acetylene gas and oxygen as the fuel to heat the work surface above the critical quenching temperature and hot and cold water have been successfully used as successive quenching mediums. It has been found that a work piece that has been heat-treated in the manner described herein possesses a surface hardness only slightly less than that it would possess if it had been quenched in one stage with cold water, but at the same time the toughness of the surface was increased and the tendency to cracking minimized.

Although a single embodiment of the invention has been shown and described herein it is to be understood that all modifications are contemplated which fall fairly within the scope of the appended claim.

I claim:

In a flame hardening head, an elongated unitary member, a fuel chamber therein extending longitudinally adjacent one edge thereof, means defining a longitudinally extending series of open-

ings from said fuel chamber through a first exterior surface of said member, a first elongated coolant chamber in said member adjacent said fuel chamber and substantially coextensive therewith, a second elongated coolant chamber in said member adjacent the side of said first coolant chamber remote from said fuel chamber and substantially coextensive with said first coolant chamber, jet directing openings along the length of each of said coolant chambers and extending from said coolant chambers through a second exterior surface of said member in the same general direction as the openings from said fuel chamber, conduit means for conducting a hot quenching medium to each end of said first coolant chamber, and further conduit means for conducting a cold quenching medium into each end of said second coolant chamber, said exterior surfaces being arranged in stepped relation to each other with said second surface being arranged to lie closer to a workpiece than said first surface.
